ATTORNEY.

UNITED STATES PATENT OFFICE.

FRANK A. GODLEY, OF PHILADELPHIA, PENNSYLVANIA.

TIMER-BRUSH.

1,333,711.

Specification of Letters Patent. Patented Mar. 16, 1920.

Application filed August 26, 1919. Serial No. 319,979.

To all whom it may concern:

Be it known that I, FRANK A. GODLEY, a citizen of the United States, residing at the city of Philadelphia, county of Philadelphia, 5 and State of Pennsylvania, have invented certain new and useful Improvements in Timer-Brushes, of which the following is a specification.

This invention has relation to a timer brush of the general type shown and described in U. S. Letters Patent #1,296,420, and has for its leading object to so improve the construction of such type of brush that the commercial value thereof is materially 15 enhanced. Other and further objects reside in the provision of general details of construction and in the provision of certain combination of parts as will hereinafter more fully appear.

20 The invention consists of the improvements hereinafter described and finally claimed.

The nature, characteristic features and scope of the invention will be more fully 25 understood from the following description taken in connection with the accompanying drawings forming part hereof, and in which:

20 Figure 1, is a view in elevation of a timer brush embodying features of the invention, 30 and

Fig. 2, is a cross-sectional view thereof.

For the purpose of illustrating my invention, I have shown in the accompanying drawings one form thereof which is at present 35 preferred by me, since the same has been found in practice to give satisfactory and reliable results, although my invention is not limited to the precise arrangement and organization of the instrumentalities as here- 40 in shown and described.

Considerable difficulty has been experienced in the trade with timer-brushes of the general type under consideration, for the reason that the tempered spring-steel arms 45 carrying the contact-brushes are continuously breaking. I have discovered that by fluting or corrugating the arms, laterally, this difficulty is obviated. While such fluted or corrugated arm may be attached to any 50 one of several forms of sleeves now upon the market, I prefer to employ a sleeve as illustrated in the drawings a description of which will now be given. The sleeve comprises a non-continuous member 10 formed from a 55 strip of metal bent to shape. One end of

such strip of metal is bent backwardly as at 10. The opposite end has stamped therefrom a lip 11 bent outwardly upon an arc of a circle and reinforced by means of a fluted or ribbed effect 12. The extremity of 60 this particular part of said sleeve is outwardly bent as at 13, which with the slotted portion 14 forms a keeper for the spring arm about to be described. The arm is designated 15 and is formed upon an arc of a 65 circle. One end of the arm is rigidly fixed to the part 10' of the sleeve, as by a screw and nut connection 16, and the free end thereof carries a brush 17 for contacting with the segments of a timer brush as is well 70 understood in the art. The arm passes under the part 13 of the sleeve, through slot 14 and is adapted to abut against the lip 11 which serves as a spring support for said arm. The arm itself is fluted or corrugated 75 laterally as at 18. Such structure serves to add strength and flexibility to the arm and at the same time permits of a certain amount of flexibility, which together with the yielding nature of lip 11 upon which the 80 arm rests, contributes to the longevity of arm and reduces the possibility of breakage to a minimum.

It will now be apparent that I have devised a novel and useful construction which 85 embodies the features of advantage enumerated as desirable in the statement of the invention and the above description and while I have in the present instance shown and described the preferred embodiment thereof 90 which has been found in practice to give satisfactory and reliable results, it is to be understood that the same is susceptible of modification in various particulars without departing from the spirit or scope of the invention or sacrificing any of its advantages. 95

What I claim is:—

1. A timer brush comprising a sleeve and a spring arm carrying a contact brush extended from said sleeve, said arm being 100 fluted or corrugated.

2. A timer brush comprising a sleeve and a spring arm carrying a contact brush extended from said sleeve said arm being fluted or corrugated laterally. 105

3. A timer brush comprising a non-continuous sleeve formed from a strip of metal bent to shape one end thereof having a rearwardly extended flange and the opposite end having a lip and a flange extended outwardly 110.

therefrom there being a slotted portion between said flange and lip and a fluted or corrugated spring arm carrying a contact brush fixed to the first mentioned flange and extended beneath the last mentioned flange and through said slot in abutting relation with said lip.

4. A timer brush comprising a non-continuous sleeve formed from a strip of metal bent to shape one end thereof having a rearwardly extended flange and the opposite end having a fluted or corrugated lip

and a flange extended outwardly therefrom there being a slotted portion between said flange and lip and a fluted or corrugated spring arm carrying a contact brush fixed to the first mentioned flange and extended beneath the last mentioned flange and through said slot in abutting relation with said lip.

In testimony whereof, I have hereunto signed my name.

FRANK A. GODLEY.
